US00D855956S

(12) **United States Design Patent** (10) **Patent No.:** **US D855,956 S**
(45) **Date of Patent:** **** Aug. 13, 2019**

(54) **SOLE STRUCTURE**

(71) Applicant: **Under Armour, Inc.**, Baltimore, MD (US)

(72) Inventor: **Greg Newman**, Baltimore, MD (US)

(73) Assignee: **UNDER ARMOUR, INC.**, Baltimore, MD (US)

(**) Term: **15 Years**

(21) Appl. No.: **29/654,630**

(22) Filed: **Jun. 26, 2018**

Related U.S. Application Data

(62) Division of application No. 29/589,412, filed on Dec. 30, 2016, now Pat. No. Des. 824,151.

CLAIM

The ornamental design for a sole structure, as shown and described.

DESCRIPTION

FIG. 1 is a bottom and front view in perspective of a sole structure showing my new design;

FIG. 2 is a bottom and rear view in perspective thereof;

FIG. 3 is a top view thereof;

FIG. 4 is a bottom view thereof;

FIG. 5 is a lateral side view thereof;

FIG. 6 is a medial side view thereof;

FIG. 7 is a front view thereof; and,

FIG. 8 is a rear view thereof.

The sole structure illustrated is a first embodiment showing a right-footed form of the sole structure for a shoe. A second embodiment of the sole structure is for the left-footed form of the sole structure for a shoe, which is a mirror image of

(Continued)

the right-footed form, and which is not illustrated. The broken line illustration of the de-emphasized environmental structure in the figures is not part of the claimed design. The dot dash line forming a boundary around the claimed subject matter forms no part of the claimed design.

1 Claim, 6 Drawing Sheets
